FIG. 5.

FIG. 9.

DOUGLAS COLLINS

Chas. K. Davies

Attorney

UNITED STATES PATENT OFFICE.

DOUGLAS COLLINS, OF SALISBURY, NORTH CAROLINA.

STONEWORKING MACHINE.

Application filed February 14, 1924. Serial No. 692,769.

To all whom it may concern:

Be it known that I, DOUGLAS COLLINS, a citizen of the United States, residing at Salisbury, in the county of Rowan and State 5 of North Carolina, have invented certain new and useful Improvements in Stoneworking Machines, of which the following is a specification.

My present invention relates to improvements in stone working machines of the multiple spindle or gang type, and the invention as herein described and illustrated is especially adapted for use in the manufacture of Durax paving blocks. It will be understood however that the principles of the invention may be embodied in machines adapted for other uses where surface treatment of stone is necessary.

In the manufacture of paving blocks of 20 the well known Durax type, a cube or chunk of granite or other hard stone measuring approximately twenty six inches is obtained from the quarry. In carrying out my invention this chunk is drilled to prepare it 25 for the use of wedges, and it is grooved or traced on one or more surfaces in order that the chunk may be broken by sledge hammer blows into rectangular slabs. These slabs are then grooved or traced at equidistant 30 lines by a machine embodying my invention, and then the grooved slab is broken into small cubes, as by a sledge hammer. These small cubes are finally broken by any suitable machine into the commercial paving 35 blocks or stones.

So far as I am aware the chunks and slabs above referred to have heretofore been drilled and grooved by hand or manual use of drills and chisels, resulting in long and 40 tedious expenditure of time and labor. By the utilization of my invention as embodied in several modifications thereof a series of holes is first drilled in the chunk; then the chunk is grooved or traced on one or more 45 surfaces by the operation of a series of chisels moving in a vertical plane; and after the traced chunk has been broken into slabs in any suitable manner, these slabs are grooved or traced by the operation of a 50 series of chisels traversing the slab in a horizontal plane.

After the chunk has been drilled and

grooved or traced, this twenty-six inch cube is broken into four slabs twenty-six inches square and six and one half inches thick. 55 Each slab is then grooved or traced in order that it may be broken into sixteen cubes of six and one half by six and one half inches, and finally each of these cubes is broken into paving stones in the form of three and a 60 quarter inch cubes.

The machines in which I have embodied my invention are designed to simultaneously drill a series of holes, and to simultaneously cut or trace a series of parallel grooves in a 65 face of a chunk and in the face of a slab, in such manner that the chunk and the slab may be broken with accuracy and uniformity.

By the use of these machines embodying 70 my invention a material saving in both time and labor is secured, and the cost of production of the paving blocks is substantially reduced.

My invention consists in certain novel 75 combinations and arrangements of parts relating to the adjusting and operating mechanism of these several machines, as will hereinafter be more fully set forth and claimed.

In the accompanying drawings I have illustrated three exemplifications of my invention wherein the parts are combined and arranged in a multiple drilling machine; a machine for cutting vertically arranged grooves; and a machine for cutting horizontally arranged grooves; according to the best mode I have thus far devised for the application of the principles of my invention. 80 85

Figure 1 is a view in side elevation of the 90 machine for tracing or chiselling grooves on lines in the horizontal surface of a slab.

Figure 2 is a front elevation of this machine.

Figure 3 is a detail view partly in section 95 showing the gang of chisels in operative position.

Figure 4 is a detail sectional view at line 4—4 of Figure 2.

Figure 5 is a view in side elevation, partly 100 broken away, of the machine for tracing or grooving the chunk in vertical lines.

Figure 6 is a detail plan view partly in section, at line 6—6 of Figure 5.

Figure 7 is a front elevation of the multiple drilling machine embodying my invention.

Figure 8 is a perspective view of a chunk 5 or cube of stone showing the drill holes and traced lines thereon.

Figure 9 is a perspective view of one of the four slabs broken from the chunk, showing the traces or grooves thereon.

10 Figure 10 is a detail plan view of the supporting frame for the machine tools, parts being shown in section for convenience of illustration.

15 Before the chunks and slabs are traced or grooved they are marked with suitable lines, and then the grooves are formed in the faces of the chunks and slabs along these lines. In the preferred manner of utilizing my invention I employ an industrial railway 20 track 1 and a suitable number of cars or trucks 2 upon which the chunks 3 and slabs 4 are placed for transportation and for the drilling and cutting or grooving operations of the successive machines hereinafter referred to.

25 The car is provided with a bed of sand for supporting the stone and the body of the car is swiveled on its truck so that it may swing in a horizontal plane on its center, 30 for the purpose of presenting various faces of a stone to a machine.

35 The machine for tracing or cutting vertical grooves on the chunk of stone or cube, as illustrated in Figures 1, 2, 3, and 4 will first be described. In this machine, as well as in the other two machines hereinafter referred to, three machine tools of well known type are used, employing a motive fluid as air or steam, and for convenience of description these machine tools may be referred to as steam-operated. Each machine tool has a standard cylinder 5, which in this case is designed to operate a bit or chisel 6 which is reciprocated longitudinally of the cylinder, 40 and the admission of motive fluid or steam to the cylinder is provided for as indicated at 7. To prevent displacement of the bit or tool, a light spring 8 is used to retain it in relation to the machine tool, and a beveled 45 cutting edge 9 is fashioned on the bit or chisel for tracing or cutting a groove in the face of the stone. The three chisels operate simultaneously and they cut parallel grooves in the faces of the chunks and slabs as indicated.

50 As illustrated in Figures 1 through 4 the machine tools are located in a vertical plane and the chisels reciprocate in the vertical plane under pressure from the interior of the respective cylinders 5.

55 The machine tools are supported for bodily vertical movement for the purpose of adjusting them to their work by a horizontally disposed supporting frame, and the machine tools are supported in this frame in such

manner that they are capable of a bodily movement in a horizontal plane to cause the chisels to traverse the face of the slab and cut the transversely extending grooves therein.

70 Thus in the three exemplifications of the invention the machine tools are adapted for bodily movement in both a horizontal and a vertical plane.

75 In Figures 1 through 4 the supporting frame for the three machine tools comprises three vertically disposed and spaced bushings 10 for the tool cylinders 5, and these bushings are rigidly connected by a horizontal bar 11. A guide frame 12 extends from the supporting frame and is fashioned with a guide sleeve 13 for the several bits or chisels.

80 At the ends of the supporting frame are fashioned slotted plates 14 which are connected with a relatively movable yoke 15, and guide bolts 16 and pins 17 of the yoke are adapted to slide in these slotted plates as best seen in Figure 3.

85 This yoke is designed as a support for the machine-tool operating devices, each of which comprises a bar 18 extending from a cross plate 19 and passing through a bearing hole 20 in the yoke. A spring 21 is interposed between the cross plate and the yoke, 90 and each bar is fashioned with an end socket-head 22 to fit over and engage the standard form of handle-head 23 of the machine tool.

95 The motive fluid for the series of machine tools is controlled by a control lever 24 having a supporting pivot 25 and pivoted at 26 to the cross plate. Bracket 26 which is attached to one of the bushings 10 is adapted to support the control lever, and the usual pawl and ratchet device 26^a is utilized to hold the control lever in adjusted position. By manipulating the lever 24 admission of motive fluid to the cylinders 5 is controlled, and a simultaneous co-operation of the machine tools is secured, for the purpose of reciprocating the chisels.

100 The supporting frame is reciprocable in a horizontal plane to cause the chisels to trace or cut grooves across the top surface of the slab 4, and therefore the supporting frame is fashioned in the form of a carriage with a pair of side two-wheel trucks as 27 which rest upon and roll over the spaced tracks or guideways 28 of the channel side beams 29. The carriage with the machine tools may be caused to reciprocate in the channel side beams by manual power applied to the tongue 30 fixed to the frame bar 11 in suitable manner and extending forwardly in position for ready access by the operator of the machine.

105 110 115 120 125 130 These channel beams are supported or suspended by a pair of oppositely arranged angular side arms 31 which are secured as

by bolts to the flanges 32 of a vertically movable head 33. As best seen in Figure 3 this vertically movable head is fashioned with a gudgeon 34 slidable in the socket 35 of the hollow bearing head 36, and the bearing head is fashioned with an integral top bolt 37 projecting upwardly in alignment with the gudgeon 34. The bolt passes through a swivel head 38 and is provided 10 with a securing nut 39.

The gudgeon is fashioned with a pair of oppositely extending cross bars 40 which project through the vertical slots 41 in the socket head for the purpose of guiding and 15 retaining the gudgeon and the frames and machine tools supported thereby when these parts are lowered or elevated.

The vertical movement of the gudgeon is accomplished by means of an adjusting 20 lever 42 which is pivoted at 43 to the socket-head 36. This adjusting lever is provided with a counterweight 44, and the lever, which is slotted at 45 is pivoted on one of the lateral bars of the gudgeon, and retained 25 thereon by a nut 46. A well known type of latch device indicated at 47 with a rack segment 48 is utilized for holding the adjusting lever in adjusted position.

The bearing head 38 at the top of the machine from which the operating parts are suspended, is a part of a flexible or foldable and extensible frame which comprises the arm 49 integral with the head 38 and pivoted at 50 to a second arm 51 which in turn 25 is pivoted through its bearing head 52 on the top bolt 53 of the standard or stationary post 54 that is supported on a suitable foundation and braced to withstand the strain imposed by the weight of the operating 30 parts of the suspended machine. The flexible frame is foldable or extensible to bring the operating parts of the machine to desired position within limits, and the bearing head 38 is made rigid with the bolt 35 45 37 by means of the set screw 55 to hold the suspended machine in adjusted position.

From the above description taken in connection with my drawings it will be apparent that the entire apparatus has a swiveled 50 support from the post 54 through the horizontally extending foldable arms 49 and 51, and the suspended machine is movable through a horizontal plane with relation to the standard 54.

55 Referring to Figures 1 and 2 the machine is shown in normal position with relation to the slab to be traced or grooved, but before operating the machine the hand grasping the handle 30 pushes the carriage to the right in Figure 1 bringing the chisels at the right edge of the slab. By pulling down on the adjusting lever 42, the gudgeon 34 and the entire apparatus depending therefrom is lowered until the chisels 9 rest upon the 60 top face of the slab, and the chisels receive

the weight of the machine tools which is thus transferred from the bushings 10 of the supporting frame or carriage. A continued pull on the adjusting lever moves the suspended parts, except the machine tools, 70 downwardly, the bushings 10 sliding on the cylinders 5 a distance equal to the depth of the grooves to be cut in the face of the stone, and the machine tools are ready for operation. The lever 42 is locked in position to 75 hold the suspended frame and carriage against vertical displacement, and then the operating lever 24 is grasped and pulled downwardly to force the tool handles 23 into the cylinders 5 to admit steam or motive fluid to the cylinders at 7 from the usual flexible pipes or hose. The admission of motive fluid to the cylinders causes the operation of the chisels with a reciprocatory motion in a vertical plane. The operating 80 lever may be locked in position, or it may be retained by one hand while the other hand grasps the handle 30, and as the chisels reciprocate and cut the slab the carriage is drawn forwardly and pushed rearwardly as required. In this manner a series of accurately spaced, parallel grooves is cut into the upper face of the slab 4 which 85 grooves will act as breaking lines for the slab when struck by the sledge hammer 90 after the tracing operation.

After the series of lines has been traced across the face of the slab, the rotatable carriage 2 with its slab may be turned at right angles, and the tracing operation repeated, this 100 second operation cutting a series of parallel lines intersecting the first series and extending at right angles thereto.

The initial step in the process of breaking up the chunk or cube 3 is performed 105 by the drilling machine illustrated in Figure 7.

The drilling machine is designed to drill the three holes in the chunk as indicated in Figure 8 and the machine embodies modified forms of the invention as disclosed in Figure 9. In the drilling machine however the bevel edged chisels 6 are displaced by the drill bits 57, the machine tools being suspended as usual by their heads above the bushings 10 of the supporting frame 11. The admission of motive fluid to the machine tools is controlled by the operating lever 24 in manner similar to the control 110 of the horizontal tracing machine.

A modified arrangement of the adjusting mechanism includes the adjusting lever 42' which is fashioned with a rectangular yoke 58 through which the pivot bars 59 of the gudgeon, as 34, project, and the lever is pivoted to the slotted, socket-head 36 at 60, back of the arms 59 in Figure 7. The shape of the arms 61 depending from the head 33 differs from the arms 31 of the horizontal 115 120 125 130

tracing machine, but they are rigid members with the supporting frame bar 11 and bushings 10.

Inasmuch as a horizontal movement of the supporting frame for the machine tools is not required the carriage feature is dispensed with, and the machine tools are adjusted and operated as heretofore described, for drilling the holes in the chunk.

10 After the chunk or cube 3 has been drilled, it is traced with grooves to prepare it for breaking into slabs 4, and these grooves preferably are fashioned by machine tools embodied in a vertically reciprocating machine as distinguished from the horizontally reciprocating carriage of the machine of Figs. 1 through 4.

In Figures 5 and 6 the modified arrangement of the principles of my invention is adapted to the machine for cutting vertical grooves in the chunk or stone cube 3, which as indicated in Figure 5 is positioned on an elevated portion of the industrial railway track and supported on the car 2. Any other suitable arrangement of the chunk with relation to the vertical grooving machine may be adopted, it being essential however as herein exemplified that the machine tools be first elevated and then permitted to move 20 downwardly by gravity for the purpose of tracing or cutting the grooves in the side of the chunk. If necessary the machine tools may be reciprocated in a vertical plane to make the cuts or grooves to the required 25 depth, and I therefore do not wish to be understood as limiting this adaptation of my invention to a single, downward, working movement of the machine tools.

The beveled edge chisels 9 are used as in 30 the horizontal cutting machine, and the admission of motive fluid or steam to the machine tools is controlled by the operating lever 24 which is pivotally supported in brackets or arms 62 attached to the cross 35 bar 11 of the machine-tool supporting-frame. The supporting frame and the chisels are adjusted to operative position with relation to the chunk of stone by an operating or adjusting lever 63 located below the supporting frame and pivoted at 64 to the fixed bracket frame 65. A slotted connection at 40 66 to the horizontally disposed yoke 67 which is rigid with the horizontally disposed machine-tool supporting-frame, permits the required movement of the lever 63, and a 45 pawl 68 and rack 69, the latter on the horizontally disposed bracket 65, hold the lever in adjusted position.

The machine tools and their supporting 50 frame, together with the levers and connections are elevated by means of motive fluid pressure, as steam or air in the vertically arranged cylinder 70 which performs the function of a support or base for the apparatus. Motive fluid is admitted to the

cylinder at its lower end through the pipe 71, and a valve 72 therein may be used to admit fluid pressure to the cylinder, as well as for the purpose of permitting discharge of the pressure therefrom when the machine is to be lowered, proper vents being provided for the cylinder to permit reciprocating movement of the piston 73 in the cylinder. The piston 73 has a rectilinear movement in the cylinder and its stem 74 which projects upwardly through the upper head 75 of the cylinder is fashioned with a horizontally disposed, flat, circular disk or head 76, cast integrally or otherwise made rigid with the central bushing 10 and cross bar 11 of the machine-tool supporting-frame. At its opposite ends the cross bar of the frame is fashioned with a pair of horizontally extending guide heads 77 with longitudinal slots 78 opening at the outer faces of the respective heads.

20 The guide slots are designed to accommodate a pair of horizontally disposed slide blocks 79 which are adapted to act as guides for the slotted heads of the supporting frame when said frame and the machine tools are being adjusted in a horizontal plane with relation to the stone chunk, through the medium of the adjusting lever 63 as described.

25 Each of the guide blocks is fashioned with an angularly disposed, integral slide block as 80, preferably alined with the cross bar 11 of the supporting frame and projecting outwardly therefrom. These slide blocks are retained within and slidable in the grooves or vertical ways 81 of the upright arms of a rectangular frame 82 which is rigid with the head 75 of the cylinder 70. Thus it will be apparent that by manipulating the adjusting lever 63 the machine tools and their supporting frame may be adjusted to operative position with relation to the adjoining vertical face of the chunk 3 in Figure 5. Then the machine tools may be operated by manipulating the lever 24, and upon the admission of motive fluid through pipe 71 to the cylinder 70, beneath the piston head 73, the operating parts of the machine will be elevated. This upward movement 30 of the operating parts of the machine, while the chisels 9 are being actuated, will cause the formation of grooves in the face of the chunk of stone along predetermined and indicated lines, and a second or return movement of the apparatus, along the same lines, may be accomplished by cutting off the supply of motive fluid to the cylinder, and permitting the weight of the suspended apparatus, imposed on the piston head, to force the piston and its stem downwardly into the cylinder. Or if desired, the apparatus may be elevated by motive fluid pressure before the machine tools are operated, and then, when the pressure of motive fluid is relieved

35 40 45 50 55 60 65 70 75 80 85 90 95 100 105 110 115 120 125 130

below the piston head 73, the weight of the suspended or elevated apparatus will cause its downward movement. With the machine tools in operation, this downward movement 5 of the apparatus causes the chisels to groove the chunk along the marked lines.

In the modified form of the invention shown in Fig. 10 means are provided for independent motion of the several machines 10 or machine tools in order that the tools may be accommodated to any irregularities on the face of the stone being worked. The cross plate is fashioned with three spaced socket heads 18' axially alined with the 15 respective machine tools and these socket heads project through openings in the yoke 15, the springs 21 being interposed between the cross plate and the yoke and coiled about the socket heads and performing their usual 20 functions.

These sockets or socket heads 18' receive and retain the ends of bars 22' which are alined with the socket heads and attached to the socket heads 22 that engage the handles or handle-heads 23 of the respective 25 machine tools. Between the heads 22 and a washer 23' (which washer is loose and slideable on the bar 22') a spring 19' is interposed to act as a cushion for each machine 30 tool. One end of each spring 19' is attached to a washer and the other end of each spring bears against a socket head 22 thus exerting its tension against the machine tool. By this arrangement of parts 35 the springs afford a resilient cushion or means for urging the tools against the face of the stone being worked.

It will thus be noted that each of the machine tools is capable of independent movement 40 relatively to its supporting bushing 10 along its longitudinal axis whether used in a vertical stone working machine or in a horizontal stone working machine. Thus when placed in operative position for chiseling 45 the face of a chunk or a slab, the individual tools are capable of movement against the tension of the springs 19'. If the carriage is being moved horizontally or the supporting frame 11 is being moved 50 vertically and one of the chisels encounters an elevation or depression on the face of the stone, the chisel and its machine are held to operative position. In the case of an elevation the machine tool will "give" 55 against compression of the spring 19' and if a depression is encountered the machine tool will be forced by the tension of the spring to cause the chisel to follow the depression. The chisel however continues 60 to reciprocate as it follows the contour of the face of the stone being worked and cuts the groove or traces the groove in the face of the stone.

The details of operation of the machines 65 may be arranged by the operator to insure

greatest efficiency, the required number of traversing movements of the chisels across the chunk or slab may be varied, and the number of faces of the chunks or slabs fashioned with the grooves will also be determined by the operator, to insure correct breaking of the stone by hammer blows. 70

While I have illustrated the use of three machine tools of standard or well known make, it will be understood that the number of tools used may be increased or diminished, and the machine tools may be of any commercial type adapted for the purpose. 75

Objects other than stones may be worked 80 by the utilization of the chisels, and articles other than paving blocks produced from these objects, and changes and alterations may be made within the scope of my claims without departing from the spirit of my 85 invention.

Having thus fully described my invention, what I claim as new and desire to secure by Letters Patent is

1. The combination in a stone working 90 machine with a plurality of machine tools and a relatively movable supporting frame therefor, of means for moving said frame and machine tools to adjusted position, and subsequently moving said frame with relation to the tools for gaging the cut of the tools. 95

2. The combination with a plurality of machine tools and a relatively movable supporting frame therefor, of means for moving said frame and machine tools to operative position and subsequently moving said frame with relation to the tools for gaging the cut of the tools, and means for simultaneously controlling the operation of 105 said machine tools.

3. The combination with a plurality of machine tools, a relatively movable frame, and a support, of an adjusting lever pivoted on said support and frame whereby the 110 frame and tools may be adjusted to operative position and the frame subsequently moved relatively to the tools for gaging the cut of the tools.

4. In a stone working machine the combination with a plurality of machine tools, a relatively movable frame, and a support, of an adjusting lever pivoted on said support and frame whereby the frame and machine tools may be adjusted to operative 115 position and the frame subsequently moved relatively to the machine tools to gage the cut of the tools, and means for controlling the operation of the machine tools. 120

5. In a stone working machine the combination with a plurality of motive fluid operated machine tools and an adjustable supporting frame therefor, of a relatively 125 movable yoke carried by said frame, a cross plate having a series of control bars guided 130

in said yoke and operative connections between said cross plate and yoke, and means for actuating said cross plate for co-action of the control bars with said machine tools to control the admission of motive fluid thereto.

6. In a stone working machine the combination with a plurality of machine tools and their supporting frame having slotted plates, of a yoke supported in said slotted plates and movable relatively thereto, a cross plate having a series of control bars guided in said yoke and springs interposed between said cross plate and yoke, and means for actuating said cross plate for co-action of the control bars with said machine tools to control admission of motive fluid thereto.

7. The combination in a stone working machine with a suspending socket-head having lateral slots, of a supporting frame having a cross-head and a gudgeon supported in said socket-head, cross arms on said gudgeon, and a lever pivotally connected to one of said arms for moving said frame as described.

8. The combination with a plurality of machine tools and a supporting carriage therefor, of means for moving said carriage and machine tools to operative position in a line at an angle to the movement of the carriage and for subsequently moving said carriage along the axial lines of the machine tools for gaging the cut of the said tools.

9. In a stone working machine the combination with a vertically adjustable head and arms and horizontally disposed tracks carried by said arms, of a wheeled carriage supported on said tracks; a plurality of machine tools supported in the carriage, and adjusting mechanism for moving said head to bring the carriage and machine tools to operative position and for subsequently

moving the carriage with relation to the tools for gaging the cut of the tools.

10. The combination, with a vertically adjustable frame having tracks and a horizontally movable carriage on said tracks, of a machine tool supported in said carriage, means for moving the frame carriage and tool to operative position and for subsequently moving said carriage and frame with relation to the tool for gaging the cut of the tool.

11. In a stone working machine the combination with a supporting frame having a series of spaced bushings, of a plurality of machine tools each having a head for supporting a tool in a bushing, and means for moving said frame and machine tools to operative position and for subsequently moving said frame with relation to the tools for gaging the cut of the tools.

12. In a stone working machine the combination with a supporting frame having a series of spaced bushings, of a plurality of machine tools each having a head for supporting a tool in a bushing, a cross head and means thereon for suspending said supporting frame, and means for moving said head whereby the frame and machine tools are adjusted relative to the work and the frame subsequently adjusted to gage the cut of the tools.

13. In a stone working machine the combination with a supporting frame having a series of spaced bushings, of a plurality of machine tools supported in said bushings, means for moving said frame and tools to operative position, and independent resilient means for holding each tool in operative position with relation to a stone.

In testimony whereof I affix my signature:

DOUGLAS COLLINS.
